US00D889481S

(12) **United States Design Patent** (10) **Patent No.:** **US D889,481 S**
Bae et al. (45) **Date of Patent:** **** Jul. 7, 2020**

(54) **DISPLAY SCREEN OR PORTION THEREOF WITH GRAPHICAL USER INTERFACE**

(71) Applicant: **SAMSUNG ELECTRONICS CO., LTD.**, Suwon-si, Gyeonggi-do (KR)

(72) Inventors: **Hyojin Bae**, Seoul (KR); **Hyunsuk Seo**, Seoul (KR); **Wansoo Lim**, Seongnam-si (KR)

(73) Assignee: **SAMSUNG ELECTRONICS CO., LTD.**, Gyeonggi-Do (KR)

(**) Term: **15 Years**

(21) Appl. No.: **29/662,530**

(22) Filed: **Sep. 6, 2018**

Related U.S. Application Data

(63) Continuation of application No. 29/563,880, filed on May 9, 2016, now Pat. No. Des. 829,219.

CLAIM

The ornamental design for a display screen or portion thereof with graphical user interface, as shown and described.

DESCRIPTION

The sole FIGURE is a front view of a display screen or portion thereof with graphical user interface showing our new design.

The outer broken lines in the FIGURE depict a display screen or portion thereof and form no part of the claimed design. The remaining broken lines in the FIGURE depict portions of the graphical user interface that form no part of the claimed design.
